UNITED STATES PATENT OFFICE.

CHARLES H. EUTEBROUK, OF BOSTON, MASSACHUSETTS.

FIRE-ARM.

SPECIFICATION forming part of Letters Patent No. 289,521, dated December 4, 1883.

Application filed September 11, 1883. (No model.)

To all whom it may concern:

Be it known that I, CHARLES H. EUTEBROUK, a subject of the King of Belgium, residing at Boston, in the county of Suffolk, 5 State of Massachusetts, have invented a certain new and useful Improvement in Fire-Arms, of which the following is a description sufficiently full, clear, and exact to enable any person skilled in the art or science to which 10 said invention appertains to make and use the same, reference being had to the accompanying drawings, forming a part of this specification, in which—

Figure 1 is a side elevation, representing the 15 guard-lever closed, the hammer down, and the gun discharged; Fig. 2, a like view, representing the guard-lever open, the hammer cocked, and the barrel elevated to receive the cartridge; and Fig. 3, a vertical longitudinal section, representing the guard-lever closed, the barrel 20 loaded and depressed, and the hammer cocked.

Like letters and figures of reference indicate corresponding parts in the different figures of the drawings.

25 My invention relates to that class of breech-loading fire-arms in which the barrel is raised and depressed and the hammer cocked by means of the trigger guard-lever; and it consists in a novel construction and arrangement 30 of the parts, as hereinafter more fully set forth and claimed, by which a more effective device of this character is produced than is now in ordinary use.

The nature and operation of the improvement 35 will be readily understood by all conversant with such matters from the following, its extreme simplicity rendering an elaborate description unnecessary.

In the drawings, A represents the barrel; 40 B, the stock; C, the trigger; D, the hammer; E, the mainspring; G, the guard-lever, and H the needle or striker-pin. These parts being all old and well known in other fire-arms, no claim is made thereto when in and of themselves considered. The guard-lever G is pivoted in the stock at x, and is elongated to form 45 the projection m, which is adapted to enter and work in a corresponding recess, i, in the rear end of the flange J, projecting downwardly from the barrel A. A stud or arm, K, projects upwardly from the body of the lever

G, nearly at right angles thereto, and is provided at its outer end with the backwardly-projecting lip or flange v, as shown in Figs. 2 and 3. The hammer D is rounded on its 55 front edge, l, and provided near its lower side with a notch or stop, n, into which the flange v on the arm K falls, thereby preventing the guard-lever from being opened or thrown back too far in cocking the gun and elevating the 60 barrel to receive the cartridge L. A retractor, M, is provided; but as it is constructed and operated in the usual manner no novelty is claimed for it, and a more explicit description is deemed unnecessary. The body of the lever 65 G, projection m, and stud or arm K are integral, or formed of one piece, thereby greatly simplifying the construction of this part of the gun, rendering it more durable and less liable to get out of order than guns of this 70 character in which the guard-lever and devices for elevating and depressing the barrel and cocking the hammer are composed of two or more pieces in the usual manner.

In the use of my improvement, to load the 75 gun the guard is open or thrown back to its fullest extent, as shown in Fig. 2, the projection m working in the recess i, to elevate the barrel A and bring it into a position to receive the cartridge, the arm K at the same time being brought into contact with the rounded face l of the hammer, thereby forcing the hammer back until the trigger C falls into the notch t in its lower side and the gun is cocked, the flange v at the same time entering the 85 notch n and preventing the lever from being opened too far. After the cartridge is inserted the lever is closed to depress the barrel and bring it into position for firing, leaving the hammer at full-cock, as shown in Fig. 3, the 90 lever being secured by the snap-catch r, near its outer end, in the usual manner.

I do not confine myself to the use of the flange v and notch n, as these may be omitted, if desired, although I deem it preferable to 95 use them.

It will be understood that the trigger C and hammer D are properly pivoted, and that the spring E is arranged to act in conjunction therewith in the usual manner.

Having thus explained my invention, what I claim is—

1. The combination, substantially as described, of a pivoted gun-barrel, a hammer, and a guard-lever having an integral projection at its inner end, which projects under the barrel, for raising the same, and an integral lateral arm near its pivot, adapted for contact with the hammer, for cocking the same simultaneously with the raising of the barrel.
2. The combination, substantially as set forth, of a pivoted gun-barrel provided at its rear end with a depending recessed lug, a hammer, locking mechanism therefor, and a pivoted guard-lever having a projection at its inner end, which operates on the recessed lug for raising the barrel, and a lateral arm near its pivot, adapted for contact with the hammer, for cocking the same simultaneously with the raising of the barrel, said projection and arm being integral with the guard-lever.
3. The combination, substantially as set forth, of a pivoted gun-barrel provided near its rear end with a depending recessed lug, a hammer provided with a stop on its front face,
- 15 a hammer-locking mechanism, and a pivoted guard-lever having a projection at its inner 25 end, which operates on the recessed lug for raising the barrel, and a lateral arm near its pivot, adapted for contact with the hammer, for cocking the same simultaneously with the raising of the barrel, and with said stop for 30 arresting the movement of the lever.
4. The combination, substantially as set forth, of the pivoted gun-barrel A, provided near its rear end with a depending recessed lug, J, the hammer D, provided with stop n, 35 the spring E for operating the hammer, the trigger C, a firing-pin, and the guard-lever G, provided with integral projection m, adapted to engage the recessed lug, and integral lateral arm K, near its pivot, adapted to engage the 40 hammer.

CHARLES H. EUTEBROUK.
